A. BRAUNSTEIN

PAINT BRUSH

Filed April 19, 1924

Inventor.
Arthur Braunstein

By Watson E. Coleman
Attorney

UNITED STATES PATENT OFFICE.

ARTHUR BRAUNSTEIN, OF CASPER, WYOMING.

PAINTBRUSH.

Application filed April 19, 1924. Serial No. 707,692.

To all whom it may concern:

Be it known that I, ARTHUR BRAUNSTEIN, a citizen of the United States, residing at Casper, in the county of Natrona and State of Wyoming, have invented certain new and useful Improvements in Paintbrushes, of which the following is a specification, reference being had to the accompanying drawings.

10 This invention relates to paint brushes and more particularly to that type of brushes ordinarily employed for careful close work, such as sign or card painting and the like, and has for an important object thereof the provision of a brush head adapted for this use having means whereby it may be engaged with a holder similar to the ordinary pen holder so that a plurality of heads may be carried and employed with 15 a single holder, each head being adapted for a particular type of work.

A still further object of the invention is to produce as an article of manufacture a brush head of this character.

25 A still further object of the invention is to provide a device of this character which may be simply and cheaply produced, readily transported, and which will enable housing of the brush heads in a suitable receptacle carried in the pocket so that the entire painting outfit may be carried upon the person of the painter from place to place.

30 These and other objects I attain by the construction shown in the accompanying drawings, wherein for the purpose of illustration is shown a preferred embodiment of my invention and wherein:—

35 Figure 1 is a perspective view showing a complete paint brush constructed in accordance with my invention;

40 Figure 2 is an enlarged perspective view of one of the brush heads in the course of construction;

45 Figure 3 is a transverse sectional view through the brush head;

Figure 4 is a plan of the blank employed in the formation of the brush head;

50 Figures 5 and 6 show different manners of constructing the handle engaging shank;

55 Figure 7 shows how a plurality of such brush heads can be placed in a small receptacle for carrying in the pocket.

Referring now more particularly to the drawings, the brush element preferably consists of a rectangular felted flat pad 10. The 55 holder or shank for this brush is formed by employing a T-shaped piece of metal as shown in Figure 4, the stem 11 of the T being relatively narrow, while the head 12 is broad. This T-shaped piece may be 60 stamped from a sheet of metal and after stamping the felt pad 10 is applied to the head centrally thereof, preferably having its upper marginal edge 13 spaced from that edge of the head 12 from which the stem 11 projects, the lower edge of the felted pad 65 projecting beyond the opposite edge of the head. After the pad is placed in position the stem portion 11 is bent, as at 14, and at a point nearer the head than the end of 70 the stem portion 11, so that the end of the stem portion 11 folds back upon and holds in position against the head 12 the felted pad 10. This felted pad is of less width than the length of the head portion 12 and 75 the end portions 15 of this head are then folded back upon the pad and the extremity 16 of the stem 11 to hold the same in position. In the construction of the head portion it is preferably made of such length 80 that when folded back, as above described, the ends of the head portion overlap one another as shown. The double thickness of the stem portion formed by bending the same upon the line 14 provides a shank for 85 the brush head thus formed and this shank is shaped for engagement in the slotted opening of a pen holder or in a similar slotted opening formed in any suitable type of handle. In Figure 5 I have shown in 90 perspective a stem portion for the brush head which is flat, while that shown in Figure 6 is curved for engagement in a curved slot.

95 It will be obvious that a plurality of such brush heads may be conveniently carried in a small container 17 which may be slipped into the pocket and different brush heads substituted in the holder as desired. It will furthermore be obvious that the manner of 100 constructing the brush head proper is capable of a certain range of change and modification without materially departing from the spirit of my invention and I accordingly

do not limit myself to such specific structure as hereinbefore set forth except as hereinafter claimed.

I claim:-

5 In a brush, an absorbent pad, a T-shaped metal holder, the pad abutting the central portion of the holder, the stem of the metal holder having a reverted portion the extremity of which engages the pad to maintain

the pad in position, the ends of the metal member having reverted portions overlying the pad and the end of such stem portion, said stem portion forming a shank for engagement with the holder.

In testimony whereof I hereunto affix my 15 signature.

ARTHUR BRAUNSTEIN.
